UNITED STATES PATENT OFFICE.

SAMUEL G. GREEN, OF THE UNITED STATES ARMY.

SHOULDER-REST FOR GUNS.

1,384,386.

Specification of Letters Patent. Patented July 12, 1921.

Application filed May 7, 1919. Serial No. 295,463.

(FILED UNDER THE ACT OF MARCH 3, 1883, 22 STAT. L., 625.)

To all whom it may concern:

Be it known that I, SAMUEL G. GREEN, 5 lieut., Ordnance Department, United States Army, a citizen of the United States, stationed at Washington, D. C., have invented an Improvement in Shoulder-Rests for Guns, of which the following is a specification.

The invention described herein may be 10 used by the Government, or any of its officers or employees in prosecution of work for the Government, or by any other person in the United States, without payment of any royalty thereon.

15 The object of my invention is to provide a novel shoulder-rest for machine guns, etc., in which the shoulder-rest-piece may be quickly and easily adjusted relative to its support, to meet the requirements of different operators.

With this object in view, the invention resides, generally stated, in a shoulder-rest embodying a support attachable to a gun, and having a depending standard or post, on 25 which is mounted a slideable shoulder-rest-piece, the standard and the shoulder-rest-piece having a tongue-and-groove connection, and means for frictionally holding the shoulder-rest-piece in adjusted position.

30 For a fuller understanding of the invention, reference may be had to the accompanying drawings in which like reference characters designate corresponding parts throughout the several views, which latter 35 may be briefly described as follows:—

Figure 1 is a plan view of my shoulder-rest;

Fig. 2 is a view in side elevation thereof;

Fig. 3 is a bottom plan view, partly in section, thereof; and

Fig. 4 is a detail view, in side elevation, of the member which is attachable to the gun, and which carries the support for the shoulder-rest-piece.

45 Referring, now, in detail to the drawings:

1 designates a tubular member having a longitudinal slit 2, extending from one end thereof and terminating short of the other end. This tubular member is slipped over 50 an extension of the stock of the machine-gun, and is frictionally clamped thereto by means of a clamping-bolt 3, hinged at 4 to a strap 5, passing partly around the member 1, at the split portion thereof, and having ears 6, 6, between which said clamping

bolt 3 is adapted to project, the threaded portion 7 of the bolt carrying a wing nut 8, which may be screwed against the ears 6, 6, thereby tending to contract the tube 1 and bind it upon the extension of the stock. Said 60 tubular member and the means for securing the same to the stock of the gun form no part of this invention.

Carried by the tubular member 1, at the end thereof opposite the strap 5, is a depending standard or post 9, provided with a longitudinal slot 10, and with longitudinal grooves 11, 11 in the sides thereof.

Slidable on said standard 9 is a shoulder-rest-piece comprising a slide 12, having a lateral wing 13 preferably transversely corrugated throughout a portion of its length, as shown at 14. The slide is preferably constructed of sheet metal stamped to shape, and is provided with longitudinal flanges or lips 15, 15 entering the grooves 11, 11. Thus, the standard 9 and the slide 12 have a tongue-and-groove connection.

Suitable means are provided for frictionally holding the slide in adjusted position, 80 and in this instance, such means preferably comprise a clamping bolt 16, passing transversely through the sides of the slide 12 and having a cross-sectionally squared portion 17, to fit the slot 10 and prevent rotation of the 85 bolt therein, and having, also, a threaded portion 18, on which is threaded a wing nut 19. In operation, by screwing up the nut 19 on the bolt 17, the sides of the slide 12 will be caused to frictionally bind against the 90 sides of the post 9, and thereby frictionally hold the slide in adjusted position.

It will be noted that, by the construction described, I have provided a shoulder-rest of exceedingly simple construction in which the 95 shoulder-rest-piece is easily and quickly elevated or lowered on the support (such as the post or standard 9), to suit the requirements of different operators.

Having thus fully described my invention, what I claim as new and desire to secure by Letters Patent, is:—

1. A shoulder rest including a member attachable to the rearwardly projecting cylindrical portion of a machine gun stock, a depending standard integral with said member at the rear end thereof, said standard provided with a longitudinal slot, a shoulder rest piece slideable on said standard and means passing through the slot and engaging 110

the shoulder piece for clamping the piece in selected position upon the standard.

2. A shoulder rest, including a tubular member adapted to telescope over the rearwardly projecting cylindrical extension of a machine gun stock, means for clamping said member to said stock, a depending standard integral with said member at the

rear end thereof, said standard provided with a longitudinal slot, a shoulder rest piece slidable on said standard and means passing through said slot and engaging the shoulder rest piece for clamping the piece in selected position upon said standard.

SAMUEL G. GREEN.
